Patented Sept. 28, 1920.

UNITED STATES PATENT OFFICE.

GEORGE R. PRATT, OF WILLISTON, NORTH DAKOTA.

SANITARY DRINKING-FOUNTAIN.

1,354,064.

Specification of Letters Patent. Patented Sept. 28, 1920.

Application filed March 22, 1918. Serial No. 223,985.

To all whom it may concern:

Be it known that I, GEORGE R. PRATT, a citizen of the United States, residing at Williston, in the county of Williams, State 5 of North Dakota, have invented certain new and useful Improvements in Sanitary Drinking-Fountains; and I do hereby declare the following to be a full, clear, and exact description of the invention, such as 10 will enable others skilled in the art to which it appertains to make and use the same.

This invention relates to drinking fountains.

The object of the invention is to construct 15 a drinking fountain from which a number of people may drink at one time, and which will furthermore provide accommodations for adults and children without requiring the former to bend or stoop to an uncom- 20 fortable degree and without causing the latter to either stretch or climb to reach the mouth piece.

With the above general object in view, and such others relating to the particular 25 arrangement of parts and details thereof as may hereinafter appear, my invention will now be fully set forth and described, reference being had to the accompanying drawings.

30 In the drawings:—

Figure 1 is an elevation of a drinking fountain constructed according to my invention,

Fig. 2 is a vertical section thereof,

35 Fig. 3 is a section on line 3—3 of Fig. 1, and

Fig. 4 is a fragmentary elevation taken at right angles to Fig. 1,

40 Fig. 5 is a detail perspective view showing the basin mounted.

Referring more particularly to the drawings, 1 represents a vertical casing which provides a pedestal and tubular housing for the various parts of the invention, and is 45 preferably constructed of two semi-cylindrical separable sections.

Extending vertically through the casing 1 is a stand pipe 2 which feeds water to a compartment or receptacle 3 which closes 50 the top of the casing 1, and provides a reservoir from which water is distributed through to a feed pipe 4 to the several drinking nozzles as will hereinafter appear. The receptacle 3 is preferably a spherical globe 55 which will provide an ornamental and serviceable element. At the entrance of the

stand pipe 2 into the receptacle 3 is a valve 5 which is controlled by a float 6 whose function it is to close the valve before the receptacle 3 is entirely filled with water so 60 that a reduction in the water pressure is effected between that which rises in the stand pipe 2 and that which flows to the several drinking nozzles. Within the casing 1 and supported by the pipes 2 and 4 is a 65 sectional structure 7 which provides a series of alternating vertical sections 8 upon opposite sides of the fountain and shelves 9 which traverse the casing 1.

Each of the vertical sections 8 is provided 70 with an elongated slot 10 within which is movably mounted a slide element 11 which provides a support for a drinking nozzle 12 and also a conduit for transmitting water to the nozzle 12 from a flexible tube or pipe 75 13 which is connected to the feed pipe 4 behind its respective vertical section 8. Also suspended from the slideable coupling element 11 is a basin 14, as by a stem 15, the basin 14 underhanging the nozzle 12 so as to 80 catch the waste water therefrom. The lower end of the basin is provided with a discharge nipple to which is attached the flexible conduit 16, the latter having its opposite end directed into the casing 1, so as to discharge 85 the waste water into the latter, whence it finds its way to a drainage pipe at the bottom of the casing.

The slide couplings 11 fit the slots 10 so 90 that there is a slight loose movement which permits the coupling to tip within the slots, and furthermore, the nozzles 12 are of such construction that when the couplings 11 are tipped downwardly by the weight of the nozzles, the nozzles will be positioned to 95 direct the water issuing therefrom into the basins 14. Also, the nozzles carry the shields 17 which are hinged thereto so that they may be turned upwardly when the nozzles are lifted so as to clear the latter to 100 give the drinker convenient access thereto, these shields normally depending over the discharge ends of the nozzles so as to deflect the water to the basin. While the nozzles 12 and the basin 14 may be lifted 105 by means of the shields 17, the basins 14 are also provided with handles 18 which may be employed to lift the movable assemblage into convenient drinking position.

In the construction of the above described 110 fountain, a convenient number of drinking nozzles and accompanying basins are mount-

ed upon the standard, so that a number of persons may be accommodated, the positions of the nozzles providing accommodations for adults and children.

5 The further adjustment permitted by the side wall relation of the nozzles in the sections 8 provides an arrangement whereby a person may lift a fountain nozzle into favorable drinking position where the arrangement does not naturally provide one.

10 The nozzles 12 may be of any type required by different institutions or city governments while still permitting the apparatus of my invention to perform all of the 15 functions required of it. While the water which is supplied to the fountains is received directly from the water supply, so that it has the usual high pressure of such supplies, this pressure will be broken down 20 in the traverse of the reservoir 3 to the nozzles, so that persons who drink from the fountain are not splashed or sprayed by the nozzle.

What I claim as my invention is:—

25 1. A drinking fountain, comprising in combination, a casing serving as a waste pipe, a feed pipe therein, a plurality of horizontally extending nozzles mounted in the

casing for vertical sliding movement and for vertical tilting movement therein, a 30 basin carried by each nozzle, a flexible connection between each nozzle and the feed pipe, and a flexible connection between each basin and the waste pipe.

2. A drinking fountain, comprising in 35 combination, a casing serving as a waste pipe, a feed pipe therein, a plurality of lateral nozzles mounted in the casing to slide vertically and for vertical tilting movement with respect thereto, a plurality 40 of basins also slidably with respect to the casing, flexible connections between the feed and waste pipes and the nozzles and the basins respectively, and shields extending over the discharge ends of the nozzles for 45 normally diverting the waste from the nozzles into the basins, said shields being movable out of such position to expose the nozzle ends.

In testimony whereof, I affix my signature in the presence of two witnesses.

GEORGE R. PRATT.
